UNITED STATES PATENT OFFICE

LUTHER C. BALDWIN, OF PROVIDENCE, RHODE ISLAND, ASSIGNOR TO U. S. BOBBIN & SHUTTLE COMPANY, OF PROVIDENCE, RHODE ISLAND, A CORPORATION OF RHODE ISLAND

TENSION DEVICE FOR SHUTTLES

Application filed October 12, 1928. Serial No. 312,112.

This invention pertains to weaving shuttles and more particularly to yarn tension devices for such shuttles. While certain of the broader features of the invention may find embodiment in other specific arrangements at large, for example as disclosed in my copending application Serial No. 312,111, filed October 12, 1928, I have herein chosen to illustrate the tension device of the present invention as embodied in a removable block or housing of metal or other material independent of but adapted to seat within a cavity in the shuttle body. By reason of the peculiar conditions under which a shuttle operates, it is far more difficult to keep a uniform tension on the moving yarn than in most other situations, since such apparently negligible quantities as the inertia of the tension element become of importance in shuttle tensions in view of the extremely sudden changes in velocity and directions of movement of the shuttle. In the small space available for the reception of a shuttle tension device, the utmost compactness of arrangement is essential, thus precluding the use of many types of tension elements which are found useful in other situations. The parts should be sturdy and capable of long continuous use, although readily replaceable when worn or broken. The tension should be so designed as to permit ready and rapid threading, and to avoid cutting or breaking of the yarn, especially when the direction of motion of the shuttle is changed. The yarn engaging elements should be so arranged and of such material as to resist rapid cutting or wear by the moving yarn; inertia effects should be minimized; and the device should be simple and inexpensive to construct and install.

In accordance with the present invention I provide a tension device possessing all of the above desirable characteristics together with other features more fully pointed out hereinafter.

In the accompanying drawings I have illustrated certain embodiments of the invention by way of example and in the drawings.

Fig. 1 is a fragmentary plan view of a

weaving shuttle having a preferred form of tension device embodying the present invention installed therein;

Fig. 2 is a fragmentary side elevation of the shuttle illustrated in Fig. 1;

Fig. 3 is a side elevation of a removable tension block embodying a preferred form of the present invention;

Fig. 4 is a section, to larger scale, on the line 4—4 of Fig. 3;

Fig. 5 is a horizontal section, to larger scale, on the line 5—5 of Fig. 3;

Fig. 6 is a side elevation similar to Fig. 3, but illustrating another embodiment;

Fig. 7 is a rear end elevation of the device shown in Fig. 6;

Fig. 8 is an elevation showing the device of Fig. 6 from the opposite side; and

Fig. 9 is a vertical section, to larger scale, substantially on the line 9—9 of Fig. 6.

Referring to the drawings and particularly to Figs. 1 and 5 inclusive, the numeral 1 designates the shuttle body, having the usual bobbin cavity 2 and tension receiving cavity in its end portion 3. The shuttle is also provided with a yarn delivery eye 4 at the outer end of a passage leading laterally from the tension cavity.

In accordance with the present invention the tension elements are carried by a block 5 having a longitudinal yarn passage or channel 6, and having the downwardly and laterally extending threading slot 7, together with such other and usual thread guiding and retaining parts as are common in devices of this type, including, for example, the downwardly extending front horn H. The block 5 is also preferably provided with a downwardly extending boss 8 adapted to seat in a socket in the bottom of the tension receiving cavity, and with a transverse opening 9 for the reception of the usual retaining bolt 10 (Fig. 1).

In accordance with the present invention the block or housing 5 is provided with a substantially vertical and preferably cylindrical bore 11 (Fig. 4) extending upwardly from its bottom surface. Within this bore I arrange a pair of relatively movable tension elements 12 and 13 respectively. Pref-

erably these elements are of thin material and light in weight although hard and wear resistant. Thus sheet steel heat treated or otherwise hardened is suitable for the purpose. Preferably these tension elements are of cylindrical form, fitting within the bore 11. I prefer to make them of hollow cup shape, thus minimizing their weight. The lower member 13 is inverted, and when the block 5 is in position in the shuttle, this lower member rests upon the bottom of the tension cavity, although upon removal of the block from the cavity both tension elements are free to be withdrawn from the bore 11. The upper tension element 12 is arranged to slide freely in the bore 11 and is urged downwardly toward the lower element 13 by means of a spring 14. The upper end of this spring preferably bears against a shoulder on an adjusting screw 15 engaging a screw-threaded bore 16 in the upper part of the block 5. In order to hold the screw 15 in adjusted position I may if desired provide retaining means as, for example, a set screw 17 engaging a screw-threaded bore in the block 5. Under some circumstances the spring 14 may be dispensed with, the weight of the friction element 12 being depended upon to secure the proper tension. In such case a series of interchangeable members 12 may be provided, of different weights adapted for selective use in accordance with the size of the yarn or the degree of tension required. Preferably the members 12 and 13 are provided with substantially flat end surfaces opposed to each other and between which the yarn Y passes, such opposed surfaces being substantially in the plane of the bottom of channel 6. To facilitate the entrance of the yarn between the members 12 and 13 I prefer to round the corners of the elements 12 and 13 where their end surfaces merge into their cylindrical surfaces, thus providing a flaring throat 18 into which the yarn may be pulled in order to wedge the members 12 and 13 apart.

In accordance with the arrangement shown in Figs. 1 to 5, the yarn engaging surfaces of the members 12 and 13 are continuous (without projections or perforations) and as these elements are substantially flat and parallel, they bear with equal pressure over that portion of the yarn which is disposed between them. The pressure being thus distributed over a substantial length of yarn produces a more uniform tension than would be the case were the yarn pinched at a single point, and as the yarn extends in a substantially straight run across the tension member 13, there are no turns or bends tending to produce areas of abnormal thickness which would localize the pressure.

In order to guide the yarn properly in a straight run across the tension elements I

prefer to provide a pair of fixed guide pins 19 and 20 (Fig. 5) disposed respectively at opposite sides of the tension elements. The pin 20 is arranged closely adjacent to one side of the channel 6 while the pin 19 is disposed at a point substantially laterally opposite to the yarn delivery eye 4. The yarn thus moves in a substantially straight run from the channel 6, across the surface of the tension element 13, and then makes a substantially right angle in turning about the post 19 on its way to the yarn delivery eye 4. 70

In the arrangement shown in Figs. 6 to 9 inclusive the block 5^a is substantially similar to the block 5 above described and is provided with a bore 11^a for the reception of the upper and lower tension elements 12^a and 13^a similar to the elements 12 and 13 above described. 80

In this instance the elements 12^a and 13^a are provided with centrally disposed apertures in their end or bottom walls for the reception of a pin 21 extending downwardly from the screw 15^a engaging a threaded bore 16^a in the block. A spring 14^a may be arranged within the bore 11^a, bearing at its lower end against the tension element 12^a and at its upper end against the web 22 forming the upper wall of the cavity 11^a. 90

In the arrangement just described the 95 guide post 19 and also the post 20, if desired, may be omitted, since the pin 21 which passes down through the friction elements constitutes a guide about which the yarn passes on its way to the lateral guide eye. While this latter arrangement may be desirable under some circumstances, I prefer that disclosed in Figs. 1 to 5 inclusive, since in the latter case the yarn passes in a straight run across the tension elements, thus ensuring more uniform tension than when yarn is constrained to make a sharp bend or angle at a point between the tension elements. 100

As already pointed out, the cup-shaped tension elements are made very light in 110 weight so as to avoid inertia effects such as might pinch, cut, or break the yarn when the direction of movement of the shuttle is suddenly changed. As the tension elements are disposed within the block 5 they are not 115 readily affected by accumulations of lint or oil and are fully protected against mechanical injury. The tension spring, if such be used, is also housed in and protected, although its tension is readily adjustable. The tension elements are of simple, durable, and compact form, taking up but little room in the shuttle body and being readily formed of material having wear-resistant characteristics. The tension device thus provided is of a type which permits ready and automatic threading; it is relatively inexpensive to construct; and when positioned in a shuttle body 125 is not injuriously affected by the heavy 130

shocks and blows to which the shuttle is subjected in use.

While I have shown certain desirable embodiments of the invention, it is clear that various changes in size, shape and relative arrangement of parts may readily be made without departing from the spirit of the invention.

I claim:

10 1. A shuttle tension comprising a housing having an elongate bore therein, a pair of tension elements fitting in slidable engagement with the walls of the bore within said bore, one at least of said elements sliding longitudinally of said bore toward and from the other tension element, said elements having continuous yarn engaging faces, bearing with equal pressure over that portion of the yarn disposed between them, and means 15 silently urging the movable element toward the other.

20 2. A shuttle tension comprising a housing removably secured in the shuttle and having an elongate bore, a pair of tension elements fitted within said bore, one at least of said elements sliding longitudinally of the bore toward and from the other element, and guide means in the shuttle beyond the confines of said elements for determining the 25 paths of a yarn passing between them.

30 3. A shuttle tension comprising a housing having an elongate cylindrical bore, and a pair of cylindrical tension elements fitted in slidable engagement with the walls of said bore, one at least of said elements sliding longitudinally of the bore toward and from the other element, the opposed surfaces of said elements being uninterrupted and free from projections or apertures and bearing throughout with equal pressure over 35 that portion of the yarn disposed between them.

40 4. A shuttle tension comprising a housing removably secured in the shuttle and having an elongate bore therein, and a pair of tension elements fitted in slidable engagement with the walls of said bore, one at least of said elements sliding longitudinally of the bore toward and from the other element, the opposed surfaces of said elements being smoothly polished and imperforate and bearing throughout with equal pressure over that portion of the yarn disposed between them.

50 5. A shuttle tension comprising a housing removably secured in the shuttle and having an elongate cylindrical bore, a pair of hollow, cup-like tension elements fitted in slidable engagement with the walls of said bore, said elements having opposed substantially flat ends constituting yarn engaging surfaces, one at least of said elements being slidable longitudinally of the 55 bore, a spring seated within the hollow of

the latter element, and means for adjustably tensioning the spring.

6. A shuttle tension comprising a housing removably secured in the shuttle and having an elongate cylindrical bore and a 70 pair of thin-walled, light-weight, cup-like tension elements fitting in slidable engagement with the walls of the bore in said bore, said elements having flat parallel opposed end walls constituting yarn engaging surfaces, the junction between the said end walls and the side walls of said elements being smoothly rounded to provide a flaring throat to facilitate entrance of the yarn 75 between the elements.

7. A shuttle tension comprising a block adapted to be seated in a cavity in a shuttle body, said block having a bore extending upwardly from its bottom face, a pair of tension elements fitting within said bore, the lower of said elements resting upon the bottom of the cavity in the shuttle body when the block is assembled with the latter, the upper tension element sliding vertically 80 in the bore and means for holding said elements tensionally in engagement, said elements being removable from and replaceable in the block without altering the tension exerted by such means during operative 85 engagement thereof.

8. The combination with a shuttle body provided with a cavity for the reception of tension means of a block fitted within said cavity, the block having a cylindrical bore extending upwardly from its lower face, 90 and a pair of cup-like tension members slidably fitting in said bore, the lower of said members being inverted and adapted to rest on the bottom of the cavity in the shuttle body when the block is seated therein.

9. The combination with a shuttle body provided with a cavity for the reception of tension means, of a block fitted within said cavity, the block having a cylindrical bore, a pair of relatively movable tension elements slidably fitting in said bore, said elements having opposed substantially flat yarn engaging surfaces, and yarn guide elements in said shuttle independent of said block for directing the yarn in a path extending between said elements.

10. The combination with a shuttle body provided with a cavity for the reception of tension means, of a block fitted within said cavity, the block having a cylindrical bore, 120 a pair of relatively movable cylindrical tension elements slidably fitting in said bore, said elements having substantially smooth, imperforate yarn engaging faces, and yarn guide members disposed at opposite sides of said tension elements and constraining the yarn to move in a substantially rectilinear path extending between said elements.

11. In combination with a shuttle body provided with a cavity for the reception 125

of tension means and having a passage leading from said cavity to a lateral guide eye, a block fitting within said cavity, the block having a bore extending upwardly from its bottom, a pair of relatively movable tension elements disposed within said bore and having yarn engaging surfaces parallel to the plane of the bottom of said bore, a spring urging one of said elements toward the other, a screw for adjusting the tension of the spring, means for retaining the screw in adjusted position, and a pair of yarn guides so arranged as to direct the yarn longitudinally of the shuttle body and between said tension elements and laterally to the guide eye.

12. A tension device for shuttles comprising a block having a longitudinal channel for the passage of the yarn, a pair of relatively movable tension elements adjacent to the forward end of the channel, said elements having opposed substantially flat yarn engaging surfaces disposed adjacent and parallel to the plane of the bottom of said channel, said elements having rounded edges providing a throat for the entrance of the yarn between them, the block having a threading slot leading downwardly and laterally into said channel, and a pair of spaced fixed guides for determining the path of the yarn between the tension elements.

Signed by me at Providence, Rhode Island, this 9th day of October, 1928.
